UNITED STATES PATENT OFFICE.

IRA B. HARKEY, OF NEW ORLEANS, LOUISIANA.

DESIGN FOR A BOTTLE.

Application filed November 5, 1923. Serial No. 7,681. Term of patent 7 years.

To all whom it may concern:

Be it known that I, IRA B. HARKEY, a citizen of the United States, and resident of New Orleans, in the parish of Orleans and State of Louisiana, have invented a certain new and ornamental Design for a Bottle, of which the following is a specification, reference being had therein to the accompanying drawing, forming a part thereof.

In said drawings,

Fig. 1 is an elevation of one side of the bottle embodying my design.

Fig. 2 is an elevation of the opposite side of the same bottle.

Fig. 3 is a cross section of the body of the bottle.

What I claim is:

The ornamental design for a bottle, as shown.

In testimony whereof I hereunto affix my signature.

IRA B. HARKEY.
